CLAIM

The ornamental design for an intake screen, as shown and described.

DESCRIPTION

FIG. 1 is a perspective view of an intake screen according to our new design;

FIG. 2 is a front elevational view of the intake screen of FIG. 1;

FIG. 3 is a top plan view of the intake screen of FIG. 1;

FIG. 4 is a bottom plan view of the intake screen of FIG. 1;

FIG. 5 is a left side elevational view of the intake screen of FIG. 1;

FIG. 6 is a right side elevational view of the intake screen of FIG. 1;

FIG. 7 is a partial cross-sectional view of the intake screen of FIG. 2 taken substantially along line 7-7; and,

FIG. 8 is an enlarged detailed view of a portion of the intake screen of FIG. 2.

FIGS. 1-8 illustrate a first embodiment of our novel design suitable for use on the left side of a vehicle. Our novel design also includes a second embodiment suitable for use on the right side of a vehicle, which is mirrored symmetrical to FIGS. 1-8 and therefore not separately illustrated.

The broken lines shown in the drawings illustrate portions of the intake screen that form no part of the claimed design.
